DRILL

Walter C. Rea, New York, N. Y., assignor to Detachable Bit Corporation of America, New York, N. Y., a corporation of Delaware

Application April 8, 1930. Serial No. 442,497

10 Claims. (Cl. 255—64)

This invention relates to drills of the type comprising a drill rod and a bit detachably carried therewith, and more particularly to means for coupling such rod and bit.

- 6 It has already been proposed to use a threaded coupling member to secure a bit to a drill rod in constructions of this character. When such a drill is percussively driven, as is usual, it is desirable that the impacts be transmitted directly 10 from rod to bit or bit to rod, to relieve the coupling and the threads of such forces. At the same time, the tendency of the coupling, due to rotation of the drill, to become wedged or jammed on either the rod or the bit is to be avoided.
- 15 The principal object of this invention is, therefore, to provide an improved construction whereby these desired advantages are secured and which is simple and inexpensive to manufacture, rugged and durable in service, and capable of being readily disassembled into its parts even after the drilling operation. A feature of the present invention resides in the location of the means to prevent wedging entirely within the bit and rod.

Other objects and advantages of this invention 25 will be apparent from the following detailed description of a preferred embodiment thereof, reference being had to the accompanying drawing wherein:

Fig. 1 is a longitudinal, central section through 30 the lower end of a drill rod, Fig. 2 is a side view of a coupling member and Fig. 3 is a side view of a bit. Fig. 4 is a longitudinal, central section through the parts when assembled. Fig. 5 is a section on the lines 5—5 of Fig. 4 looking in the 35 direction of the arrows. Fig. 6 is an end view of the construction, looking upwards with reference to Fig. 4.

There is shown at 1, a portion of a drill rod which is hollow as at 2 and formed with internal 40 threads 3. A coupling member or stud 4 is formed with threads 5 and 6 at either end thereof and a flange 7 of annular shape intermediate the end of the stud. A bit 8 is provided with internal threads 9 for cooperation with the threads 45 6. The drill rod and bit are formed with enlarged openings 10 and 11, respectively, adapted to receive the flange 7, which is shown in abutment with shoulder 13.

It will be seen that the threads 3 extend for 50 greater distances than the threads 5 so that when the portions are assembled the stud or coupling member does not abut against the upper end of the rod within the opening but rather the flange 7, when the stud is at its uppermost position abuts against the shoulder 12. The threads

on the stud all run in the same direction so that when the drill is rotated in a given direction, in this case, counter-clockwise, when looking down, the tendency is for the stud to be turned into the drill rod and the bit on to the stud. The threads 60 are shown as the so-called undulatory type but although this form is preferred, it is not essential.

The flange 7 is of such dimensions that the height of its face 7a is less than the combined heights of side faces 10a and 11a of the enlarged 65 openings 10 and 11, but greater than either of the last named faces. When the parts are so proportioned a certain amount of travel is permitted the coupling member without danger of its flange becoming wedged against rod or bit. In 70 this construction, the face 14 of the rod abuts directly against the face 15 of the bit. A slight clearance 16 is shown between the face 7a of the flange 7 and the surrounding portions of the rod and bit but this is not essential, as the parts may 75 fit snugly. A passage 17 is provided in the drill rod for the passage of liquid therethrough as is customary in the art.

Another feature of my improved construction lies in the provision of a cutting edge 18 on the 80 lower end of the coupling member. I have found that this edge acts not only as auxiliary to the cutting edges on the bit as the latter wear, but also prevents stalling of the bit against uncut portions of the material being drilled.

Although I have described the specific embodiment of my invention in considerable detail, I do not wish to be limited save by the scope of the appended claims.

What I claim is:

1. In a device of the character described, the combination of a drill rod and bit each internally threaded in the same direction, a coupling member threaded for cooperation therewith, shoulders formed within the rod and bit, and a flange 95 on the coupling member for abutment with either of said shoulders when the parts are assembled, said flange being entirely enclosed within rod and bit, and being of less height than the combined heights of the side faces of said shoulders, 100 but greater than either of the latter, the rod being threaded to a greater extent than the threads on the coupling whereby the bit and rod are in abutment and the coupling may ride in either direction.

2. The combination of a drill rod and bit having a central opening extending therethrough, each threaded, a coupling member threaded for cooperation therewith, shoulder means entirely within the rod and bit when assembled adapted to 110

- permit the coupling member to ride a predetermined distance in either direction, and an auxiliary cutting edge on the lower end of said member. 3. In a rotary impact drill, the combination of 5 two tubular sections, in end to end abutting relation, the bore of one of said sections being enlarged at the end adjacent the other section to form a recess with parts of the sections forming shoulder stops, a coupling having opposite ends 10 in threaded engagement with the sections and having a flange disposed in said recess between said shoulders, spaced from one of the shoulders, and coacting with the shoulders to limit the movement of the coupling relative to the sections. 15 4. In a rotary impact drill, the combination of 20 two separable sections, one constituting a drill rod and the other constituting a bit, in end to end abutting relation, a coupling connecting the two sections and in threaded engagement with one of the sections, said coupling having a slight 25 freedom of rotary and axial movement relative to the section with which it is threaded, stop means for permitting and limiting such slight freedom of movement of the coupling and one end of the coupling being exposed through the bit and said exposed end provided with a cutting edge. 5. In a rotary impact drill, the combination of 30 two detachable sections, disposed in end to end abutting relation, each of said sections being internally threaded with the threads in one section terminating in spaced relation to the adjacent end of the section to leave a smooth, unthreaded portion at the end of the section, a male 35 coupling member enclosed within the sections, having opposite ends engaging the threads on said sections and provided with a flange extending into said smooth unthreaded portion and said coupling adapted to be rotated into position to 40 locate the flange in spaced relation to one of the sections thereby to permit a limited axial movement of the coupling relative to the abutting sections. 6. In a rotary impact drill, the combination of 45 a bit provided at one end with cutters forming a main cutting area, said bit also provided with a bore extending axially therethrough and provided with threads, a one piece rod constituting a combined male coupling and supplemental drill provided with threads, said threaded end intruded 50 into the bore of the bit engaging the threads in the bore thereof and said bit adapted to be threaded onto and off the intruded end of the coupling, said rod provided adjacent its mid-length with an outstanding flange forming a shoulder in abutting engagement with the bit, the portion of the rod projecting externally of the bit provided with drill rod engaging means and said rod provided at the end intruded into the bit with cutting edges extending substantially 55 in the plane of the cutting edges of the bit and substantially centered within the main cutting area. 60 7. In a rotary impact drill, the combination of 65 two tubular sections in end to end abutting relation and provided with stop faces, the bores of said sections being threaded, a male coupling having opposite ends in threaded engagement with the sections and having a flange adjacent its midlength and positioned between the threaded ends, said flange having opposite sides facing said stop faces and one of said sides spaced from its opposing stop face. 8. In a rotary impact drill, the combination of 70 a tubular drill rod and bit in end to end abutting relation, said drill rod and bit provided with opposing stop faces axially spaced apart to form an annular recess, the end of the drill rod which engages the bit provided with a threaded socket, a male coupling member having opposite ends in threaded engagement with the drill rod and bit and provided with a flange contained in said recess and with one side of the flange in spaced 75 relation to the stop face on the drill rod to provide a clearance therebetween, the threaded portion of said socket having a length greater than the length of the portion of the male member intruded therein measured from said side of the flange to the extreme end of the intruded portion 80 whereby the male member is free to turn until the flange engages the stop face on the drill rod and thus take up the clearance before the end of the male member engages the end of the socket. 9. In a rotary impact drill, the combination of 85 a tubular drill rod and bit in end to end abutting relation to form a joint extending at right angles to the axis of rotation of the drill, the portion of the drill rod and bit on opposite sides of the joint 90 being threaded with a screw thread of undulatory and continuously curved contour, the portion of the drill rod and bit forming the joint having less cross sectional area of material than the portions provided with the threads, a member 95 for coupling together the drill rod and bit and provided at opposite ends with a similar form of screw thread for engaging the threads on the drill rod and bit, the end of the member intruded into the bit provided with a cutting edge, the mid portion of the coupling member disposed at the joint 100 and being of maximum cross sectional strength of material and having greater cross sectional area of material than the threaded end portions. 10. In a percussively driven rotary drill, the 105 combination of a drill rod and bit in end to end abutting relation with the abutting ends provided with aligned threaded sockets, the abutting portion of the drill rod and bit each having less cross sectional area of material than the portions 110 provided with the threaded sockets, and a male coupling member having opposite ends in threaded engagement with the sockets provided at one end with a cutting edge and provided intermediate its threaded ends with a portion of maximum 115 cross sectional area of material extending across the joint formed by the abutting ends of the drill rod and bit. 120
